Atty.

UNITED STATES PATENT OFFICE.

SAMUEL T. FROTHINGHAM, OF ALLSTON, MASSACHUSETTS, ASSIGNOR TO FIBRE MANUFACTURING COMPANY, OF BOSTON, MASSACHUSETTS, A CORPORATION OF MASSACHUSETTS.

WATER-CLOSET SEAT.

1,352,058.

Specification of Letters Patent.

Patented Sept. 7, 1920.

Application filed August 20, 1919. Serial No. 318,635.

To all whom it may concern:

Be it known that I, SAMUEL T. FROTHINGHAM, a citizen of the United States, and a resident of Allston, in the county of Suffolk 5 and State of Massachusetts, have invented a new and useful Improvement in Water-Closet Seats, of which the following is a specification.

My invention relates to water closet seats 10 and more especially to means for securing hinges to the same.

Heretofore it has been found in practice 15 that screws and other attaching means employed for securing hinges to water closet seats, especially those formed of wood covered with celluloid and those made up of layers of fiber, cannot be firmly anchored in the seat and become loosened after a short period of use.

20 The object of the present invention is to provide a device for anchoring the hinge attaching means in the seat, and to this end my invention comprises a flanged attaching device, such as a tubular interiorly threaded 25 sleeve which is embedded in the seat and with which the hinge attaching means co-operate, as for example by being threaded thereto.

The drawings which accompany and form 30 a part of this specification illustrate one embodiment of my invention that has proven satisfactory in practice, although it will be understood that various modifications may be made therein without departing from the 35 spirit of my invention.

In the drawings—

Figure 1 is an elevation of a water closet seat embodying my invention. Fig. 2 is a plan view on an enlarged scale of the under- 40 side of the seat and hinge. Fig. 3 is a plan view of the upper side of said seat and hinge with a portion of the outermost layer of the material of the seat removed. Fig. 4 is a section on the line 4—4 of Fig. 2.

45 In the particular drawings selected for more fully disclosing my invention 1 represents a water closet seat which may be formed of wood covered with celluloid or layers of fiber 2, 2', 2'', secured together in the usual

way by cement, or of any other suitable material, my invention, while particularly adaptable to composite seats, being capable of application to seats of any character.

The hinge 3 is shown as attached to the seat in the present instance by screws 6 which are threaded into the sockets 4, the latter being embedded in the material of the seat and provided with flanges 5 which preferably abut the outermost layer 2'' of fiber. In the form shown in the drawings the screws 60 are passed through the lateral flanges of the hinge and coöperate with two threaded sockets 4 although it has been found possible in practice to employ but a single socket and to thread the screw 6' which passes through 65 the end of the hinge into the same. Preferably the layer 2' is countersunk to receive the flanges of the sockets.

It will be obvious that by means of my invention the seat is securely clamped between 70 the hinge and the flanges of the sockets and that the screws being firmly anchored in the seat but not being threaded into the material thereof, cannot readily become loosened in use.

Having thus described an illustrative embodiment of my invention without however limiting myself thereto what I claim and desire to secure by Letters Patent is:

1. The combination with a water closet 80 seat formed of layers of material, of a hinge, an interiorly-threaded sleeve passing through a plurality of said layers, a flange on the inner end of said sleeve, said flange abutting one of said layers, and a screw passing 85 through said hinge and threaded to said sleeve.

2. The combination with a water closet seat formed of layers of material, of a hinge, a sleeve passing through a plurality of said 90 layers, a flange on the inner end of said sleeve, said flange abutting one of said layers, and fastening means coöperating with said sleeve and said hinge.

In testimony whereof, I have hereunto 95 subscribed my name this 19th day of August, 1919.

SAMUEL T. FROTHINGHAM.
